(57) **CLAIM**

The ornamental design for a nasal interface, as shown.

DESCRIPTION

FIG. 1 is a front perspective view of an embodiment of a nasal interface according to our new design;

FIG. 2 is a front elevational view of the nasal interface shown in FIG. 1;

FIG. 3 is a rear perspective view of the nasal interface shown in FIG. 1;

FIG. 4 is a top plan view of the nasal interface shown in FIG. 1;

FIG. 5 is a bottom plan view of the nasal interface shown in FIG. 1;

FIG. 6 is a left side elevational view of the nasal interface shown in FIG. 1; and,

FIG. 7 is a right side elevational view of the nasal interface shown in FIG. 1.
